Patented May 13-1851

Mathewit S. Backer
design for Clock frame or case
1851.

Ans. 372

Nathaniel A. Bachelor New York - ©

Letters Patent No. 372. Dated May 13. 1851

The schedule referred to in these Letters Patent and making part of the same

To all whom it may concern:

Be it known, that I,

Nathaniel A. Batchelor, of New York, in the County and State of New York, have invented or produced a new and Original design for a "Clock Case or frame", and I do hereby declare the following is a full and exact Description of the same, reference being made to the annexed drawing making a part of the Specification.

A male figure (a) in a standing position, a female seated on a rock (b) with a dog at the left (c), a tree (d), and a rock (f) make up the top part of the design. The centre of the design is an opening for a Clock face or the face itself as (m) and this is completely surrounded with ornamented raised scroll work, as (e) The third part is made up of a centre of raised shell and scroll work as (g) and is surrounded by other shell scroll and flower work as (h) all in raised relief work: below and above the third part are mouldings in raised shell work. Fourth is a plain flat, or moulding (i) surmounted upon feet consisting of scrolls extending entirely across the lower part of the design as (k) the above completing the whole design.

What I claim as my production, and desire to secure by Letters Patent, is this combination of figures, placed in the manner described, so as to form the front of a block frame, or case
